(57) **CLAIM**

The ornamental design for a holder for portable electronic device as shown and described.

DESCRIPTION

FIG. 1 is a front, bottom and right side perspective view of a holder for portable electronic device showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear, top and left side perspective view of the holder for portable electronic device; and,

FIG. 9 is another rear, top and left side perspective view, shown in a condition of use with an exemplary portable electronic device.

The dashed broken lines in the drawing depict portions of the holder for portable electronic device that form no part of the claimed design.

The dot-dot-dash broken lines shown in FIG. 9 depict environment that forms no part of the claimed design.
